J. I. TUTTLE

CALCULATING MACHINE

Filed April 20, 1925

John I. Tuttle Inventor

By Herbert E. Smith

Attorney

UNITED STATES PATENT OFFICE.

JOHN I. TUTTLE, OF SPOKANE, WASHINGTON.

CALCULATING MACHINE.

Application filed April 20, 1925. Serial No. 24,310.

To all whom it may concern:

Be it known that I, JOHN I. TUTTLE, a citizen of the United States, residing at Spokane, in Spokane County and State of Washington, have invented certain new and useful Improvements in Calculating Machines, of which the following is a specification.

The present invention relates to improvements in calculators of that type utilizing a pair of concentric disks having a single axis or axial center. One of the disks is provided with a primary scale or graduations and the other with an auxiliary scale or graduations for the purpose of forming a vernier scale especially adapted for use in calculating percentages, fractions and interest in bookkeeping, as well as for use by engineers and others in calculating stresses, loads, strains and other problems or projects in engineering or science.

The primary object of the invention is the provision of an instrument of this character which is compactly arranged, simple in construction and operation, durable, and comparatively inexpensive in cost of production.

The invention consists in certain novel combinations and arrangements of parts as will hereinafter be more fully set forth and claimed.

In the accompanying drawings I have illustrated one complete example of the physical embodiment of my invention, wherein the parts are combined and arranged according to the best mode I have thus far devised for the practical application of the principles of my invention.

Figure 1 is a plan view of the instrument.

Figure 2 is an edge view indicating the instrument as being in upright position.

Figure 3 is a transverse sectional view of the instrument showing its removable cover in place.

Figure 4 is an enlarged detail sectional view at the center of the primary and auxiliary disks.

Figure 5 is a detail plan view enlarged at the center of the auxiliary disk showing radiating slots therein and tangential slots in the primary disk for use in adjusting the relative positions of the disks.

Figure 6 is a top plan view of the locking device of Figure 4 for rigidly connecting the two disks for rotary movement.

Figure 7 is a detail view of one of the supporting arms for the instrument.

In carrying out my invention I utilize a housing 1 of a suitable material and preferably rectangular in shape with rounded corners. The housing or casing is provided with a removable cover 2 used as a shield or protection against dust or breaking, but of course removed when the calculator is to be used.

The instrument is capable of use in upright position, horizontal position, or in angular positions between these two principal positions, the horizontal position being shown in Figure 1 and the vertical or upright position being shown in Figure 2.

In the horizontal position the instrument lies flat, while in upright position it is supported erectly by means of a pair of spaced arms 3 and 4 secured on a hinge pin 5 in bearings at the underside of the bottom of the housing or casing. When not in use the arms are designed to fold into depressions 6 in the casing bottom and each arm is provided with a lug 7 for engagement by a thumb nail or finger nail when it is desired to extend the arms as supports for the instrument. There is sufficient friction in the hinge to permit adjustment of the arms at various angles with relation to the casing in order that the latter may be supported in a desired tilted position.

Within the housing or casing is contained a pair of concentric, superposed disks as the primary disk 8 and the auxiliary disk 9 upon which are arranged graduations to form a vernier scale for use in calculating as by bookkeepers, engineers, and others. A glass or other transparent shield 10 having an open center 11 is provided for the disks.

The lower primary disk 8 and the upper auxiliary disk 9 are capable of relative rotary movement and adapted also to rotate together about a common center. The housing is fashioned with a ring having annular bearing flange 12 for the lower disk and annular retaining flange 13 spaced therefrom for the upper or auxiliary disk and the glass shield. The shield or glass plate 10 of course is stationary while the primary disk

is rotatable on its bearing flange and the auxiliary disk, which is carried in a recess in the upper face of the primary disk, is capable of rotation relatively thereto.

5 The lower or primary disk is supported at its center to rotate upon a pointed pin or gudgeon 14 fixed in the bottom of the casing or housing, and said disk has an upper central boss 15 which terminates in a slit sleeve 10 or resilient cylindrical collar 16 in which a cam latch 17 is pivoted and provided with an exterior handle or knob 18. The auxiliary or upper disk 9 is fashioned with a central hub 19 which encases the boss 15 and its 15 resilient collar 16, and said hub terminates in a knurled head 20 by means of which the upper disk may be turned when free of the lower or primary disk, and by means of which both disks may be turned when they 20 are frictionally coupled together by action of the cam latch or lock. By turning the cam 17 to horizontal position in Figure 4 it will be apparent that the resilient collar 16 will be expanded into frictional engagement with the inner or interior wall of the hub 19 in such manner that the two will be locked to turn together. With the cam in locked position the primary and auxiliary disks may be revolved on the center pin by 30 action of the finger and thumb on the knurled head 20. With the cam released as in Figure 4 the auxiliary disk may be turned on the primary disk or both disks may be relatively rotated.

35 For close and delicate adjustment of the concentric disks a friction cone-wheel 21 is provided which is located in the housing beneath the lower disk and engages the beveled face or edge 22 of this disk. The cone 40 shaped friction wheel is carried on a shaft 23 journaled in the casing or housing, and an exterior knob or turning head 24 is used to turn the shaft and cone friction wheel for revolving the primary disk. When the 45 disks are locked together they may be rotated to various position relative to the center or score line 25 on the glass shield which intersects the axial center of the disks.

The open center glass shield exposes for 50 use a series of knobs or buttons 26 which are fixed to and project above the central portion of the auxiliary disk 9. This disk also has a series of slots 27 radiating a suitable distance from its center for co-action 55 with a series of tangentially arranged slots 28 in the primary disk beneath the slotted area of the auxiliary disk, as in dotted lines Figure 5. By inserting a stylus or pencil point in the intersection of a radial slot with 60 a tangential slot and moving the pencil toward or away from the center of the instrument it will be obvious that the disks may be relatively and oppositely rotated in either direction for adjustment of the vernier scale of the two disks.

The instrument may be used as follows: To set the calculator to figure interest on savings accounts when the rate of interest is say three per cent and the interest figured on a quarterly basis, first determine the 70 amount of interest on one dollar for three months. This amounts to .0075. The disk 8 is now turned so that 75 of its scale is directly beneath the hair line 25 of the glass shield and the disk is retained in this position. The 75 disk 9 is now turned so that the line of its scale marked 1 registers with the hair line 25 and the two disks are locked together by the action of the cam latch, with the number 80 75 on the primary disk alined with the mark 1 on the auxiliary disk. The calculator has automatically multiplied .0075 by any and all amounts regardless of size, the only limit of accuracy being the limit of the scale. It is proposed that the scale for figuring 85 interest on savings accounts be accurate up to four figures and estimate the fifth. This will permit of figuring interest on accounts on which the interest for three months does not amount to more than \$999.99. From this arrangement it will be seen that accounts up to \$133,333 can be figured and an account that is more than half this amount is seldom found.

90 By turning the two disks until the amount to be figured on the disk 9 comes directly under the hair line 25 we read the answer on the scale of the disk 8 at the point where the hair line crosses this scale. Any other rate of interest can be used it only being 95 necessary to first figure the amount of interest for the period of time that is to be used common to all accounts and proceed as above indicated.

100 If a common divisor is to be used the figure 1 on the disk 8 should be brought directly under the hair line 25. The divisor is then located on the disk 9 and brought directly under the hair line and the two disks 105 locked together. It will be found upon examination that the calculator has automatically divided any and all numbers regardless of amounts (without first knowing the amounts to be divided) by the common divisor. The answer will be correct provided 110 it contains five figures or less. To read the answer locate the amount to be divided on the scale on the disk 9 and turn this amount directly under the hair line 25. The answer 115 is the amount appearing on the scale on disk 8 directly under the hair line 25. To sum up, if a constant multiplier is to be used locate the multiplier on the scale of disk 8 and place the figure 1 of the scale on disk 9 directly against it. Lock the disks 120 together and proceed as before indicated. If a constant divisor is to be used, locate the divisor on the scale of disk 9 and place the figure 1 of the scale on disk 8 directly against it. Other problems it will be apparent may 125 130

rapidly be solved and with accuracy by proper manipulation of the parts.

Having thus fully described my invention what I claim as new and desire to secure by

5 Letters Patent is—

The combination with a center pin, of a disk having tangential slots and mounted to rotate thereon, a second disk having co-

acting radial slots and mounted to rotate on the first disk, means for locking these disks 10 together, and means for turning selectively the second disk or the pair of disks.

In testimony whereof I affix my signature.

JOHN I. TUTTLE.
